SURVEYING APPARATUS

Fred E. Patton, Redondo Beach, Calif., assignor
to The National Supply Company, Torrance,
Calif., a corporation of Pennsylvania

Application November 6, 1937, Serial No. 173,161

7 Claims. (Cl. 33—46)

This invention relates to apparatus for determining straightness of a pipe, bar, column, or other long object having a vertical axis of symmetry, and is more particularly related to an apparatus for determining the straightness of a pipe such as a section of a drill string used in the rotary process of drilling wells wherein the drill pipe to be tested is suspended from its upper end, and when in such position of suspension, is tested in one or more angular planes which pass through the axis of symmetry to determine the straightness of such drill pipe.

In the art of rotary drilling, the pipe known as a drill string is utilized. This drill string consists of a multiplicity of pipe sections secured together by connecting collars known as tool joints. The drill string is rotatably supported or suspended from a derrick positioned at the top of the well hole. The uppermost section known as the "kelly" is usually of polygonal cross-section to afford a driving connection with a machine for rotating the drill stem.

The drill string carries at its lower end a drilling bit and the drill string is formed of pipe sections so that drilling fluid may be pumped through the drill string and out holes formed in the drilling bit in order that the drilling bit in its operation may operate under the influence of the drilling mud.

In operation this drill string is subject to very severe service and failure and breakage is not uncommon. The weight of such drill string during operation may exceed one hundred tons as suspended within the derrick and the length of such drill string may, and often does, exceed five to ten thousand feet in length. Failure of such drill stems or in the tool joints which connect the sections results in expansive "fishing" operations, or may even result in the loss of the hole.

It has been found that one of the principal causes of failure of such a drill string is a bent section in the drill stem. Upon rotation this bent section turns eccentrically and sets up stresses that soon cause failure and breakage. A bent drill collar, as well as a bent section, is liable to, and often does, result in such failure.

In testing such drill strings, collars, etc., it is advantageous to be able to test the straightness of such sections of pipe and collars as they are being lowered into the well or connected in the drill string in order that a determination may be made of their true condition at the time of their use. An apparatus which is to be utilized in determining the straightness of such drill

stem at the time of use must be capable of use during the operation of making up the drill stem without materially interfering with the operation of adding sections to the drill stem.

It is therefore an object of this invention to provide an apparatus which may be used for the determining of straightness of each section of drill string at the time it is being raised to position to be added to the drill string prior to its being lowered into the bore hole.

Another object of the present invention is to provide an apparatus for determining the straightness of sections of a drill string, which apparatus includes a target member which is adapted to be mounted upon the drill string section near its upper end as such section is being raised into its position of suspension, and a means which is adapted to be applied to the drill string near its lower end from a position near the floor of the well derrick and which is operable in connection with such target means by mere application to the drill string in order to determine the condition of straightness of said drill string section.

Another object of this invention is to provide an apparatus for determining the straightness of a section of drill string prior to its being added to the drill string and which apparatus includes a target means which is adapted to be applied to the upper end of the drill string as it is being lifted into position of suspension within the well derrick and which target means includes a plurality of angular related target arms carrying target indicators which are utilizable in connection with an observing apparatus adapted to be applied to the pipe near the floor of the derrick so that the condition of straightness of the pipe may be determined in several planes.

Another object of this invention is to provide an apparatus for determining the straightness of a pipe, which apparatus is susceptible to use on pipes or bars having square or circular cross-section without requiring adjustments to be made in the device as applied to such bars or pipe for the purpose of permitting such determinations of straightness to be made.

Another object of this invention resides in the provision of an apparatus for determining the straightness of a section of pipe or the like, which apparatus includes a target member which is associated with a light source and a sighting instrument whereby the target reading is made visible to an observer by a reflected light.

Other objects and advantages of this invention will be apparent from the following detailed description of a preferred embodiment.

thereof as illustrated in the accompanying drawing.

In the drawing:

Figure 1 is a general perspective view of a section of drill string as suspended within a well derrick and illustrating a surveying apparatus embodying this invention as applied to, and used in, checking the straightness of such section or "stand" of drill pipe.

10 Figure 2 is a sectional elevation of a preferred form of sighting apparatus embodying my invention illustrating the same as adapted to a broken section or "stand" of drill pipe.

15 Figure 3 is an end view of the apparatus as illustrated in Figure 2.

Figure 4 is an end elevation of a target embodied in my invention illustrating the same as adapted or applied to a section of drill pipe and illustrating the same in horizontal section.

20 Figure 5 is a plan view of a modified form of target embodied in my invention.

Figure 6 is a side elevation of a modified form of target illustrated in Figure 5.

25 Figure 7 is a plan view of a portion of the target illustrating the same as viewed through the sighting apparatus embodied in my invention.

In the drawing 1 indicates a "stand" or section of a drill string illustrated as suspended by means of a well elevator 2 from a hook 3. This "stand" 30 or section of drill string is illustrated in position within a well derrick (not shown) as the same would be positioned preparatory to adding the same to the drill string which extends into a well hole.

35 The section or "stand" of drill string 1 is usually raised in the derrick from a horizontal position preparatory to adding the same to the drill string. As the drill pipe is raised to its suspended position, a target 4, or a plurality of angularly arranged targets 4, are applied to the 40 pipe so that the target arms extend outwardly from the axis of the pipe and are angularly arranged one relative to the other. If the stand 1 of the drill stem is standing within the well derrick, the targets 4 may be applied to the upper end by the derrick man.

The observer 5 standing upon the derrick floor then applies the sighting device 6 to the pipe in position so that the telescope 7 thereof lies substantially parallel with the axis of the section 1. 50 The sighting device 6 may be equipped with an illuminating means 8. The telescope 7 is formed with a right-angle eye-piece 9. The observer 5 holds the sighting device 6 in position on the section 1 to view one of the targets 4 through the 55 telescope 7. Each of the targets 4 includes a plurality of outwardly spaced indicators 10 which are illuminated by the lighting device 8. By observing which of these indicators lies upon the 60 reference line 11 of the telescope, the operator is enabled to determine whether or not the section 1 is straight or bent in the particular plane in which the observation is being made. By moving the sighting device 6 around to a second position upon the section 1 until the second target 4 is viewed in the same manner, the operator is enabled to determine quickly the condition of straightness of the section 1 without materially delaying the operation of adding the section 1 to the drill string. If the pipe section 1 is 65 straight and is then connected with the drill string, the targets 4 may be removed from the upper end of the drill string by the observer 5 as the stand or section 1 is lowered into the well hole to a position where the targets 4 may be 70 reached by the observer 5.

The telescope 7 is mounted upon the frame of the sighting device 6 in position so that the longitudinal axis of the telescope 7 will align with, or be parallel with, the principal axis of the pipe 1. In order to so position the telescope 5 7 with reference to the pipe 1, the sighting device is provided with a pair of longitudinally spaced brackets 12, each of which is formed with a 90° V-notch 13. The V-notches 13 of the brackets 12 are so formed that upon mere holding of the sighting device 6 firmly against the stand 1 or the drill collar, the longitudinal axis of the telescope 7 is positioned parallel and in alignment with the axis of the stand 1.

10 The telescope is formed with a focusing adjustment 14 which may be of any suitable or desirable construction as is well understood in the art.

15 The lighting device 8 as carried by the sighting device 6 may be of any suitable or desirable construction and is herein illustrated as including a flashlight of ordinary construction operated by batteries and including a switch 15 which, in the embodiment shown, is mounted upon the frame of the sighting device 6. The cross-hair 20 or reference line 11 is carried within the telescope 7 in a manner well understood in the art and as this invention is not particularly directed to the construction of such telescope 7, it is believed that it would serve no useful purpose particularly to describe or set forth in detail the construction of this well known instrumentality.

25 The targets 4 are preferably formed with two angularly extending legs 16 formed to provide a V-notch 17 between them similar to the V- 30 notch 13. The targets are releasably held in position by means of a clamping means consisting of a strap 18 provided at its free ends with an adjustment clasp 19 and held intermediate its ends within the body of the target 4 by means 35 of a spring 20 secured in position as indicated at 21. The spring 20 acts to hold the strap 18 under tension to thereby maintain the target 4 firmly in position against the periphery of the pipe stand 1. Each of the targets 4 includes the 40 outwardly extending target arm 22 along which the indicators 10 are spaced. The indicators 10 as illustrated include a plurality of reflectors which may be formed of different colored glass. The central reflecting indicator 23 may be, for 45 example, a white glass with two adjacent reflectors lying immediately on each side of the reflectors 23 formed of red glass and the two outer reflectors may be formed of another colored glass, such for example, as green glass. The central reflector 23 is positioned at the same distance 50 from the axis of the pipe upon the target 4 as is the axis of the telescope 7. Thus as indicated in Figure 7, when the central or white reflector indicator 23 lies upon the hair-line 11, the indication is that the stand 1 is, in the particular plane of the test, straight. Should the hairline 11 lie away from the center of the reflector 23, either 55 toward the red, green or other colored reflectors 10, the indication is that the pipe is bent in the 60 particular plane in which the test is being determined.

65 A measure of the deviation from the theoretical straightness of the pipe 1 is given by the number of reflectors 10 between the cross-hair 11 70 and the white reflector 23 and the direction of the bend either concave or convex is indicated by the position of the white reflector as to the hair- or reference line 11. Thus if the white light 23 is on the side of the reference line toward 75

the pipe, the indication is of a concave bend. Conversely, if the white light is upon the opposite side of the reference line 11, the indication is of a convex bend in the pipe. By taking two or more determinations at different angles by the use of the multiple target 4, an indication of the exact condition and direction of bend in the stand 1 may be had. It will be noted by reference to the drawing that when the sighting instrument 6 and targets 4 are positioned at opposite ends of the member 1 the determination arrived at is in effect a measure of the co-axial alignment of the ends of the member 1.

In Figures 5 and 6 I have illustrated a modified form of target which includes a semi-circular plate 25 which is notched at 26 and is held in position upon the pipe 1 by means of a flexible strap 27 releasably connected at its ends to hooks 28 carried by the plate 25. The ends of the flexible strap 27 are provided with eyes 29. The flexible strap 27 may be formed as a spring or of elastic material in order to hold the target in position upon the pipe 1.

The plate 25 is formed with a plurality of concentrically positioned semi-circular indicating lines 30. The advantage of this type of target is that instead of employing a multiple target including two target arms as illustrated in connection with the targets 4, only a single target is required and the worker 5 may determine the position of the straightness or bend of the pipe 1 by positioning the sighting device at a multiplicity of positions around the pipe 1 and making the tests with reference to the concentric circle 31 positioned in a manner similar to that of the white indicating reference reflector 23. The reference indicating semi-circle 31 has a radius equal to the distance of the axis of the telescope 7 from the axis of the pipe 1.

The color system described in connection with the reflectors 10 may be utilized in connection with the reference lines 30 or reference numerals may be placed upon the concentric circles so that they may be observed in the telescope 7.

Having fully described my invention, it is to be understood that I do not wish to be limited to the details herein set forth, but my invention is of the full scope of the appended claims.

I claim:

1. In a device of the class described for testing the straightness of a vertical member, the combination of, a sighting instrument having a principal optical axis, aligning means on said sighting instrument adapted to contact the exterior surface of the member in a plurality of angular positions, said aligning means acting to hold said optical axis and the axis of that portion of the member adjacent the instrument in substantially parallel relation for all such positions, a target on said member at a location vertically spaced from said instrument, scale means associated with said target including an arc of a circle, the radius of the circle being equal to the distance between said axes at the location of the sighting instrument.

2. In a device of the class described for testing the straightness of a vertical member, the combination of, a sighting instrument having its principal axis oriented in a direction substantially vertical, means including a pair of vertically spaced elements secured to said sighting instrument and adapted to contact the exterior surface of the member in a plurality of angular positions, said elements acting to hold the principal axis of the sighting instrument and the

axis of that portion of the member intermediate the elements in parallel relation, a target on said member at a location vertically spaced from said instrument, scale means on said target including a portion of a series of concentric circles, whereby the convergence or divergence of said axes at said target location may be observed at a plurality of positions on said scale means. 5

3. In a device of the class described for testing the straightness of a vertical member, a target, having in combination, a pair of legs forming a V-notch, a projecting body portion secured to said legs in symmetrical relation, said V-notch being adapted to contact the exterior surface of said vertical member so that the longitudinal axis thereof adjacent the target is at right angles to said projecting body portion, a straightness-indicating scale on said body portion, means to detachably secure the target upon the vertical member, said means including a flexible element associated with the legs of said V-notch and adapted to encircle said vertical member, and resilient means mounted within the body portion and adapted to act radially of said vertical member to hold said flexible element under tension. 25

4. In a device for measuring the straightness of a vertical suspended pipe, the combination of a target secured to the pipe near its upper end, said target including a plurality of angularly related target arms each of which is provided with 30 indicators, and a sighting device adapted to be applied to the pipe in position parallel to the axis of the pipe and along its length below said target, and adapted to be shifted around said pipe to optically position the same in vertical alignment with said target arms. 35

5. In a device of the class described for determining the co-axial alignment of the ends of a tube, the combination of a sighting instrument positioned adjacent one end of the tube and having a principal optical axis, aligning means associated with said sighting instrument and adapted to inherently maintain said optical axis substantially parallel to the axis of the said end of the tube adjacent the sighting instrument, a 45 target positioned adjacent the other end of the tube and provided with a plurality of angularly related target arms, said aligning means for the sighting instrument acting to permit the sighting instrument to be shifted around the tube in a 50 circular path in order to bring the optical axis substantially into a plane containing the axis of said tube at the point of application of said sighting instrument and at least one portion of one 55 of said target arms.

6. In a device of the class described for determining the co-axial alignment of the ends of a tube, the combination of a sighting instrument positioned adjacent one end of the tube and having a principal optical axis, aligning means 60 associated with said sighting instrument and adapted to inherently maintain said optical axis substantially parallel to the axis of the said end of the tube adjacent the sighting instrument, a target positioned adjacent the other end of the 65 tube and provided with an indicating scale, said aligning means for the sighting instrument acting to permit the sighting instrument to be shifted around the tube in a circular path in order to bring the optical axis substantially into 70 a plane containing the axis of said tube at the point of application of said sighting instrument and at least one portion of said indicating scale.

7. In a device of the class described for determining the straightness of a vertical tube, the 75

- combination of a sighting instrument positioned adjacent one end of the tube and having a principal optical axis, aligning means associated with said sighting instrument and adapted to inherently maintain said optical axis substantially parallel to the axis of the said end of the tube adjacent the sighting instrument, a target positioned adjacent the other end of the tube and provided with an indicating scale extending

radially of the tube, said aligning means comprising a pair of spaced V elements adapted to contact the outer surface of the tube and acting to permit the sighting instrument to be shifted around the tube in a circular path in order to bring the optical axis in line with said indicating scale.

FRED E. PATTON.
